Williams, Glendale, Calif.

Application September 5, 1941, Serial No. 409,666

5 Claims. (Cl. 311—84)

The invention relates to tables the height of which is adjustable. Hitherto such tables had legs which consisted of two or more parts shiftably connected to one another, whereby the length of the legs, and with it the height of the table, could be altered within certain limits. The manipulation for altering the length of the legs was complicated, especially in view of the requirement that all legs must uniformly be brought to exactly the same length for every height to which the table shall be adjusted.

Object of the present invention is to create a simple mechanism for altering the height of a table to two different levels so that the same table may be used as a dining table of height usual for this purpose, or as a lower table as preferred for serving coffee, tea, sandwiches or the like.

The table according to the present invention is provided with supporting members which are directly or indirectly connected to the tabletop in a jointed way, turnable around horizontal axes, and have two supporting surfaces of different distances from the said axes. According to which of these surfaces of the supporting members are brought into the supporting position by turning the members around their axes, the height of the table is either large or small.

With a simple convenient and pleasing mode of execution of the table according to the present invention, the supporting members are shaped as rectangularly bent legs in the approximate form of the letter L, the sides of which are of different length. This fills the requirement that the legs should be provided with two supporting surfaces of different distances from the axis. The turning axis of the joint by which such a leg is connected to the tabletop may be arranged either on the end of one of the sides of the L-shaped leg or on its vertex.

Of course it is necessary to provide means for locking the supporting members in the desired position.

In the annexed drawing there are shown two modes of execution of the invention. The first mode of execution is shown

In Figure 1 in elevation with the supporting members in such a position that the table stands up to its larger height.

In Figure 2 in a view from below,

In Figure 3 in elevation with the supporting members in such a position that the table stands up to its smaller height.

The second mode of execution is shown

In Figure 4 in elevation with the supporting

members in such a position that the table stands up to its larger height,

In Figure 5 in a view from below, and

In Figure 6 in elevation with the supporting members in such a position that the table stands up to its smaller height,

In Figure 7 a locking device for the turntable legs of the table is shown.

With the first mode of execution according to the Figures 1-3, the tabletop 1 is supported by two pairs of legs 2 each pair of which is arranged on one of the narrower sides of the right-angular tabletop. The legs are L-shaped, the one side 3 of which is longer than the other one 4. The legs of every pair are fastened to a horizontal bar 5 which is connected to a bar 6 by means of a joint 7 having a horizontal axis, this bar 6 being horizontally movable and guided in grooves 9 of a frame 8 fixed to the underside of the tabletop 1. Besides the bar 5, the two legs of each pair may be rigidly braced and connected to one another by cross-bars 8. Each pair of legs 3 can be turned around the horizontal axis of its joint 7 so as to bring it from the position shown in Figure 1 to the position shown in Figure 3. In the position according to Figure 1 the longer portions 2 of the legs stand upright and therefore the legs as supporting members, hold the tabletop 1 at a larger height than in the position according to Figure 3 where the shorter portions 4 of the legs are upright, while the longer portions 3 of the legs are lying horizontally on the floor. In order to lower the table out of the position according to Figure 1 it is only necessary to turn the legs around the joints 5 into the position as shown in Figure 3, and vice versa. This turning of the pairs of legs can be performed either when the table is lifted a little from the floor or when the table is laid sideways upon the floor.

A device for locking the legs in each of the two positions in which they have to support the tabletop may be executed in several ways. The locking device according to Figures 1-3 consists of a pawl 10 and a cam 11 fixed to the bar 5 and provided with a recess into which the end of the bolt 9 catches when the supporting members or legs 2 are in the position shown in Figure 1. In this way the legs cannot turn toward the middle of the table, nor can they turn in the opposite direction because their portions 4 are in contact with the under surface of the frame 8. The pawl 10 is fastened to a plate 12 which is horizontally movable and guided in grooves of the frame 8. In this way the plate 12 together

with the pawl 10 may be shifted into a position in which the end of the bolt catches into the recess of the cam 11 for locking the legs, or the pawl 10 may be withdrawn when the locking should be released. In the position according to Figure 3 no special locking device is necessary if the joints are executed and arranged as shown in Figure 3 because the fact that none of the two joints admits turning the legs toward the middle of the table, gives the table a sufficient stability.

The mode of execution shown in Figures 4-6 differs from the first one in the main by the fact that the legs shaped as right angles are connected to joints of the tabletop not with one of their ends as it is shown in Figures 1-3, but with their vertex.

In horizontal grooves 13 of the frame 14, fixed on the underside of the tabletop 15, there are guided two bars 16, each of which carries joints 17 with a horizontal axis to which the vertex of two leg-systems 18 is connected. Each leg-system consists of two legs 19, 20 which are formed of one piece in the shape of a right angle or the letter L. The side 19 of this right angle is longer than the other side 20. Two such systems of legs on one side of the table form a couple or pair with the vertices of the leg-system turnable around an axle 21 of the joints 17. When the leg-systems are in the position shown in Figure 4 in which the longer sides of the leg-systems are upright and support the tabletop, the height of the table is larger than after turning the leg-systems around the vertices until the shorter sides of the legs get into the upright position, as shown in Figure 6. The bars 16 are movable in order to admit in every case a position of the leg-systems which, at the same time, secures the highest degree of stability of the table, and avoids projecting of the horizontal portions of leg-systems over the edge of the tabletop.

Also with this mode of execution locking devices for the two different positions of the leg systems may be used. Such a locking device may consist, for example, of a couple of spring-hooks 22 (see also Figure 7 which shows this couple of springs in a front view) for each of the legs.

We do not want to limit the scope of our invention to the modes of executions We have here described and represented in the drawing, for it is obvious that the movable supporting members with their two supporting surfaces of different distances from the tabletop may be executed also many other ways.

What we claim is:

1. A table comprising a tabletop, supporting legs shaped as right angles the two sides of which are of different length, and joints with horizontal axes for connecting these legs to the

table top, the legs being turnable around the horizontal axes of the said joints, in such a manner that two positions of the right angle-shaped legs may be obtained in which the longer or the shorter of the two sides of each of the legs may be brought into an upright position for supporting the tabletop in two different heights.

2. A table comprising a tabletop, supporting legs shaped as right angles the two sides of which are of different length, and joints with horizontal axes for connecting one of the ends of the legs to the tabletop, the legs being turnable around the horizontal axes of the joints, in such a manner that two positions of the right angle-shaped legs may be obtained in which the longer or the shorter of the two sides of each of the legs may be brought into an upright position for supporting the tabletop in two different heights.

3. A table comprising a tabletop, supporting legs shaped as right angles the two sides of which are of different length, and joints with horizontal axes for connecting the vertices of the right angle-shaped legs to the tabletop, the legs being turnable around the horizontal axes of the joints, in such a manner that two positions of the legs may be obtained in which the longer or the shorter of the two sides of each of the legs may be brought into an upright position for supporting the tabletop in two different heights.

4. A table, comprising a tabletop, two pairs of supporting legs, the legs of each pair being shaped as right angles the two sides of which are of different length and being rigidly connected to each other, and joints with horizontal axes for connecting the said pairs of legs to the tabletop, the pairs of legs being turnable around the horizontal axes of the joints in such a manner that the right angle-shaped legs may be brought into two different positions in which the longer or the shorter side of each leg may stand upright for supporting the tabletop in different heights.

5. A table, comprising a tabletop, supporting legs shaped as right angles the two sides of which are of different length, joints with horizontal axes for connecting the legs to the tabletop, cams fastened to the legs and having a recess, and pawls movably connected to the tabletop, the legs being turnable around the horizontal axes of the said joints in such a manner that the right angle-shaped legs may be brought into two different positions in which the longer or the shorter side of each leg may stand upright for supporting the tabletop in two different heights, the said pawls being fit to catch into the said recesses when the legs should be locked in the one or the other of the two positions into which they have been turned.
